UNITED STATES PATENT OFFICE.

JOHN G. STAMM, OF EAST CLEVELAND, OHIO, ASSIGNOR TO THE HOOVER COMPANY, A CORPORATION OF OHIO.

DESIGN FOR A VACUUM-CLEANER CASING.

Application filed July 16, 1928. Serial No. 27,504. Term of patent 14 years.

To all whom it may concern:

Be it known that I, JOHN G. STAMM, a citizen of the United States, residing at East Cleveland, in the county of Cuyahoga and State of Ohio, have invented a new, original, and ornamental Design for a Vacuum-Cleaner Casing, of which the following is a specification, reference being had to the accompanying drawings, forming part thereof.

Referring to the drawings:

Fig. 1 is a front elevational view of a

vacuum cleaner casing showing my new design;

Fig. 2 is a side elevational view of the vacuum cleaner casing of Fig. 1.

I claim:

The ornamental design for a vacuum cleaner casing, as shown.

In testimony whereof, I hereunto affix my signature, this 12th day of July, 1928.

JOHN G. STAMM.
